UNITED STATES PATENT OFFICE.

LLEWELYN M. REED, OF DUDLEY, MASSACHUSETTS, ASSIGNOR OF ONE-HALF TO
ARTHUR F. RAYNOLDS, OF WEBSTER, MASSACHUSETTS.

SWEEP-STICK-SUPPORTING FIXTURE FOR LOOMS.

Application filed February 25, 1922. Serial No. 539,068.

To all whom it may concern:

Be it known that I, LLEWELYN M. REED, a citizen of the United States, residing at Dudley, in the county of Worcester and 5 Commonwealth of Massachusetts, have invented a new and useful Improvement in a Sweep-Stick-Supporting Fixture for Looms, of which the following, together with the accompanying drawings, is a specification.

My invention relates to a shuttle driving mechanism for looms and has for its object to provide an improved arrangement for transmitting power for driving the shuttle 15 from the sweep arm to the picker stick.

In shuttle driving mechanisms as heretofore constructed, it has usually been customary to connect the picker stick to the sweep arm by means of a lug strap embracing 20 the picker stick and the upper end of a support which serves to hold the end of the sweep arm a predetermined distance above the pivotal support of the support. The power stick is preferably made adjustable 25 with respect to the pivotal support of the picker stick, so that the throw of the picker stick can be varied. In the above described arrangement of parts, both the picker stick and the sweep arm support are loosely retained by the lug strap, so that in the operation 30 of the shuttle driving mechanism, considerable loss of motion occurs with a resultant wear between the various parts, thereby necessitating frequent renewal of the 35 lug straps.

According to the present invention I propose to provide an improved shuttle driving mechanism in which the sweep arm support is connected to the sweep arm independently 40 of the lug strap, and in such a manner that lost motion between the parts of the mechanism is substantially eliminated. These, and other advantageous features of my invention will hereinafter more fully appear, reference being had to the accompanying drawings in which,

Fig. 1 is a view in side elevation of the end portion of a loom provided with a shuttle driving mechanism embodying my invention.

Fig. 2 is an enlarged view of a portion of the parts shown in Fig. 1.

Fig. 3 is an end view of the parts shown in Fig. 2.

Fig. 4 is a plan view of the parts shown in Fig. 2.

Fig. 5 is a horizontal sectional view along the line 5—5 of Fig. 2.

Fig. 6 is a perspective view of my improved fixture for connecting the support to the sweep arm.

Like reference characters refer to like parts in the different figures.

Referring to the drawings, a portion of the frame of a loom is indicated at 1 upon which is supported a shuttle box 2 of any well known type. A picker stick 3 is pivotally mounted on a stud 4 carried by a bracket 5 projecting outwardly from the loom frame 1, and the picker stick 3 is adapted to be moved back and forth within the shuttle box 2 by means of a sweep arm 6 which is adapted to receive a reciprocatory movement from any suitable source of power, not shown. The parts of the loom described thus far form no part of the present invention and obviously may be of different construction if so desired.

As best shown in Figs. 2 and 4, the picker stick 3 is embraced by a U-shaped lug strap 7, the ends of which are secured to the sweep arm 6 by means of a bolt 8. An adjustable sweep arm support 9 is also pivotally mounted on the stud 4 and the upper end thereof is connected to the sweep arm 6 by means of a fixture 10 which, as best shown in Fig. 6, consists of a flat base portion 11 which is provided with a central opening 12 for receiving the bolt 8 which secures the lug strap 7 to the sweep arm. The base portion 11 is further provided with ears 13 which are adapted to embrace one side of the lug strap 7 when the base portion 11 of the fixture is held in close engagement with the lug strap 7 by means of the bolt 8, as best shown in Fig. 3.

The fixture 10 further comprises an arm 14 laterally off-set from the base portion 11 by a distance substantially equal to the thickness of the support 9. The arm 14 is provided with an inwardly projecting lug 15 which, as best shown in Fig. 5, is received in an opening 16 provided in the upper end of the support 9. With the above described arrangement of parts it is obvious that the sweep arm 6 will be held by the support 9 and definite distance above the pivotal axis of the picker stick 3, and in

order to vary this distance the support 9 is made adjustable in length by securing its lower end to an arm 17 by means of a bolt 18 received within a slot 19 provided in the arm 17.

When the sweep arm 6 is moved back and forth during the operation of the loom, it is obvious that its movement will be transmitted to the picker stick 3 by reason of its connection thereto by the lug strap 7. The throw, or amplitude of the movement of the picker stick 3, will be determined by the distance which the sweep arm 6 is held above the pivotal axis of the picker stick 3 by the support 9. When the picker stick 3 is driven by the sweep arm 6 it is obvious that there will be substantially no lost motion in the mechanism, owing to the fact that the support 9 is connected to the sweep arm 6 independently of the lug strap 7 by means of my improved fixture. Consequently, the wear of the lug strap 7 is very materially reduced, as compared with prior constructions, in which both the picker stick and sweep arm support were embraced by the lug strap. It will be readily seen that the use of my improved fixture permits of closer adjustment of the length of the picker stick, for the reason that the lug 15 definitely positions the end of the sweep arm 6 on the support, whereas in prior constructions the support was only loosely connected to the sweep arm by means of a strap. Furthermore, my improved fixture prevents the lug strap 7 from slipping down on the picker stick, owing to the fact that the ears 13 embrace the lug strap and prevent it from turning about the bolt 8.

A still further advantage to be gained by the use of my improved fixture lies in the fact that the possibility of smashes occurring in the shuttle box, due to interference between the sweep stick and the picker arm support, is substantially eliminated by con-

necting the support to the sweep arm independently of the picker stick and of the lug strap. With the possibility of such smashes substantially eliminated, it is apparent that the production of looms equipped with my improved shuttle driving mechanism will be materially increased, due to the fact that the loss of time resulting from shuttle box smashes, will be practically negligible.

From the foregoing then, it is apparent that by my invention I have provided an improved shuttle driving mechanism in which the wear on the parts is reduced to a minimum by the substantial elimination of lost motion and by which the operation of the loom as a whole is improved, due to closer adjustment of the throw of the picker stick and the substantial elimination of smashes in the shuttle box.

While I have shown my invention as embodied in a particular arrangement of the parts of a loom, it is not so limited, but is capable of being applied to other types of looms without departing from the spirit and scope of my invention. I desire, therefore, that only such limitations be imposed thereon as may come within the scope of the appended claim.

I claim,

In a shuttle driving mechanism for looms, the combination with a sweep arm, a pivotally mounted picker stick and a support pivotally mounted on the same axis as said picker stick, of a lug strap carried by said arm for loosely embracing said picker stick and a fixture carried by said sweep arm so providing a lug to which the upper end of said support is pivotally connected, and a pair of ears for positioning said lug strap.

LLEWELYN M. REED.

JOHN E. KOZLOWSKI.

Certificate of Correction.

It is hereby certified that in Letters Patent No. 1,517,314, granted December 2, 1924, upon the application of Llewelyn M. Reed, of Dudley, Massachusetts, for an improvement in "Sweep-Stick-Supporting Fixtures for Looms," errors appear in the printed specification requiring correction as follows: Page 1, line 23, strike out the word "support," second occurrence, and insert instead the words *picker* out the word "support," second occurrence, and insert instead the words *picker* and *stick*, and line 24, for the words "power stick" read *support*; page 2, lines 43 and 44, strike out the words "stick and the picker arm support" and insert instead *arm support and the picker stick*; and that the said Letters Patent should be read with these corrections therein that the same may conform to the record of the case in the Patent Office.

Signed and sealed this 13th day of January, A. D. 1925.
